(57) **CLAIM**

The ornamental design for a lighting fixture, as shown and described.

DESCRIPTION

FIG. 1 is a front left perspective view from below of a first embodiment of a lighting fixture according to the new design;

FIG. 2 is a front right perspective view from above thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top view thereof;

FIG. 8 is a bottom view thereof;

FIG. 9 is a front elevational view of a second embodiment of the lighting fixture according to the new design similar to FIGS. 1-8 with break lines indicating a symbolic break and the appearance of any portion of the lighting fixture between the break lines form no part of the claimed design;

FIG. 10 is a front elevational view of a third embodiment of the lighting fixture according to the new design similar to FIGS. 1-8 with break lines indicating a symbolic break and the appearance of any portion of the lighting fixture between the break lines form no part of the claimed design; and,

FIG. 11 is a front elevational view of a fourth embodiment of the lighting fixture according to the new design similar to FIGS. 1-8 with break lines indicating a symbolic break and the appearance of any portion of the lighting fixture between the break lines form no part of the claimed design.

The broken lines in the drawings illustrate portions of the lighting fixture that form no part of the claimed design.

The stippling shown in the figures represent translucent surfaces of the design and does not represent texture or surface ornamentation.

(Continued)

The long dash-short dash lines in the drawings represent a boundary of the claimed design and form no part of the claimed design.
